COMBINED MOTOR MOUNT AND TRANSMISSION HOUSING FOR A ROTARY TILLER OR THE LIKE

Kenneth A. Hotz, Sheboygan, and John W. Davies, Milwaukee, Wis., assignors to Gilson Bros. Co., Plymouth, Wis., a corporation of Wisconsin

Original design application Sept. 23, 1960, Ser. No. 62,254. Divided and this application Aug. 11, 1961, Ser. No. 66,628

Term of patent 14 years

(Cl. D35—2)

In the drawing:

The FIGURE is a front perspective view taken from the top and one side of a combined motor mount and transmission housing for a rotary tiller or the like embodying our new design, the opposite side being a mirror image of the side shown and the rear being substantially open.

The broken-line representation of a motor in the figure is for purposes of illustration only.

This is a division of our copending application Serial No. D.62,254, filed September 23, 1960, now abandoned.

We claim:

The ornamental design for a combined motor mount and transmission housing for a rotary tiller or the like, as shown and described.
